CLAIM

The ornamental design for an anchoring stake, as shown and described.

DESCRIPTION

FIG. 1 is a bottom, right, back perspective view of an anchoring stake showing an embodiment of my new design.

FIG. 2 is a top, left, front perspective view thereof.

FIG. 3 is a right side elevation view thereof.

FIG. 4 is a front elevation view thereof.

FIG. 5 is a back elevation view thereof.

FIG. 6 is a left side elevation view thereof.

FIG. 7 is a top plan view thereof.

FIG. 8 is a bottom plan view thereof.

FIG. 9 is a bottom, right, back perspective view of an anchoring stake showing an embodiment of my new design having a tether attachment eyelet.

FIG. 10 is a top, left, front perspective view thereof.

FIG. 11 is a right side elevation view thereof.

FIG. 12 is a front elevation view thereof.

FIG. 13 is a back elevation view thereof.

FIG. 14 is a left side elevation view thereof.

FIG. 15 is a top plan view thereof; and,

FIG. 16 is a bottom plan view thereof.

Shading lines are used to show solid structures and are not intended to indicate surface decoration.
